UNITED STATES PATENT OFFICE.

WILLIAM F. KIESEL, JR., OF ALTOONA, PENNSYLVANIA.

RAILWAY-CAR FRAME.

No. 832,486.

Specification of Letters Patent.

Patented Oct. 2, 1906

Application filed April 14, 1906. Serial No. 311,715.

To all whom it may concern:

Be it known that I, WILLIAM F. KIESEL, Jr., a citizen of the United States, residing at Altoona, in the county of Blair and State of Pennsylvania, have invented certain new and useful Improvements in Railway-Car Frames, of which the following is a specification.

This invention relates to improvements in steel railway-cars adapted for passenger, mail, and express service, my object being to provide a light, strong, and well-braced framework and outside sheathing for the car body and ends, giving to the car sides the requisite strength and stiffness where cut out for window-openings or side-door openings, said framework being especially designed with reference to applying it to an under-frame supported by a center sill without the use of body-bolsters such as described in my Letters Patent No. 809,921, dated January 9, 1906.

The several features of novelty will be more fully described hereinafter and pointed out particularly in the claims.

I attain my object by constructing and arranging the parts of the end and body framework of the cars substantially as illustrated in the accompanying drawings, wherein I have illustrated my improvements applied to a baggage-car, and in which—

Figure 1 represents a side elevation of the complete car with one-half shown in central longitudinal section; Fig. 2, a side elevation, on a larger scale, of a portion of the car, showing the outlines of the side frame members and the skeleton of the roof-frame; Fig. 3, a plan view of Fig. 2, showing the car-body in section on the line *a a* in Fig. 4; Fig. 4, a transverse vertical section of the car-body on a still larger scale and sectioned on line *b b* in Fig. 3; Fig. 5, an end elevation of the car, with parts on the left-hand side sectioned, on line *c c* in Fig. 6; Fig. 6, a plan view of Fig. 5, the upper half of said figure showing a section on the line *d d* in Fig. 7; Fig. 7, a central longitudinal section of Fig. 5; Fig. 8, a vertical section on the line *e e* in Fig. 5 looking to the right and drawn to a still larger scale; Fig. 9, a plan view of one end of the center sill and the end casting projecting therefrom; Figs. 10, 11, and 12, details showing a front elevation, vertical section, and rear elevation, respectively, of the upper-deck end side plates and supports, Fig. 11 being a section on line *f f* in Fig. 8; Fig. 13, a detail

showing one of the pressed-metal side casings for the end doors; Figs. 14 and 15, details showing the manner of building up the corner-posts and the reinforcing-castings there-in, Fig. 14 being a section on line *g g* in Fig. 5 and Fig. 15 a section on line *h h* in Fig. 14; Fig. 16, a detail of one of the upper-deck car-lines, showing the manner of applying the roof and inside ceiling-boards thereto, said figure being a section on line *i i* in Fig. 4; Fig. 17, a partial view of the under-side of said carline; Fig. 18, a detail showing the bolt and nut for the ceiling-clamp as applied to said carlines; Fig. 19, a cross-section on the line *j j* in Fig. 4, showing the manner of reinforcing the upper-deck car-lines where the longitudinal brace members are applied thereto; Figs. 20 and 21, details showing the jacking-castings which complete the outer ends of the cantaliver cross-bearers, Fig. 21 being a vertical section on the line *k k* in Fig. 1; Fig. 22, a detail showing a vertical section on the line *l l* in Fig. 1 and illustrating the manner of attaching the side posts to the side sills and underframe cross-braces; Figs. 23 to 26, inclusive, details showing the construction of the side frames where broken away for the side doors, Fig. 23 being a section on line *m m* in Fig. 2; Fig. 24, a similar section lower down on the line *n n* in Fig. 26; Fig. 25, a vertical section on line *o o* in Fig. 23, and Fig. 26 a vertical transverse section on line *p p* in Fig. 23; Fig. 27, details showing a section of the side-door casings and their reinforcing-castings on line *q q* in Fig. 4; Fig. 28, a modified form thereof; Fig. 29, a plan view, side, and end elevation of one of the upper-deck side plates; Fig. 30, similar views of one of the side-bearing braces employed where the car rests upon four-wheel trucks, such as described in my Letters Patent No. 800,921, dated October 3, 1905, and where the side-bearing castings cannot be placed directly beneath the main frame-posts; and Fig. 31, similar views of one of the side-bearing castings employed in connection with said braces.

Like numerals designate like parts in the several views.

This car-body is to be supported upon a steel underframe similar in features of construction to that described in my Letters Patent No. 809,921, previously referred to, said underframe comprising a box-girder center sill 1, consisting of a pair of I beams or channels joined at the top and bottom by

cover-plates and extending from end to end of the car. Near the ends the center sill is provided with center plates 2, where it rests upon the wheel-trucks. From the sides of the center sill, at suitable points intermediate the ends to properly support the car-body and transfer the weight thereof to the center sill, project cross-bearers 3, consisting of pairs of pressed-steel cantaliver-plates 4, the ends of said plates being joined together by jacking-castings 5, upon which rest the side sills 6, for which sills I preferably use angle-bars placed with their vertical limbs turned outward. The castings 5 are cored out for lightness and ribbed across for strength, their function being, in addition to completing the cross-bearers, to receive upon their under sides the jacks whereby the entire car-body is raised from the trucks when occasion may require, the construction of the car-frame being such that the lifting force applied by the jacks to these castings will be transmitted throughout the framework without fear of straining the car-body in any part.

At intermediate points between the cross-bearers and between the cross-bearers and the ends of the car the side sills are joined to the center sill by transverse braces 7, which are preferably of channel form, said cross-braces being run out from the center sill to the side sills at the points where the vertical frame-posts are secured thereto. (See Fig. 3.) These frame-posts 8 are of pressed steel of U-shaped cross-section, bent inward at the top to form the lower-deck carlines and provided with outside and inside cover-plates 9 and 10, said posts having been already described by me in my Letters Patent No. 809,920, dated January 9, 1906. The lower ends of these posts are pressed inward and riveted to the vertical limbs of the side sills 6, the outside cover-plates 9 being carried down and riveted in therewith at the outside of the sills, as shown in Figs. 21 and 22. The inside cover-plates 10 are carried down and flanged inwardly, said flanges being riveted to the cross-braces 7 or, where the posts rise from the cross-bearers, to the castings 5. The posts are thereby firmly secured at their bases and braced against side or end displacement. Where the cover-plates 10 rest upon the castings 5, bars 11 are passed across above the flanges and riveted in therewith to the castings and also to the flanges of the cantaliver-plates 4, said cross-bars 11 acting to further strengthen the connection between the jacking-castings and cross-bearer plates at these points.

The corner-posts of the car are built up from Z-bars 12 and 13, the bars 12 rising from the ends of the side sills and being secured to the bars 13 by the outside curved cover-plates 15. The cover-plates overlap the lower and upper side sheathing-plates 16

and 40 and the end sheathing-plates 17 where said sheathing-plates are riveted to the Z-bars 12 and 13. These corner-posts are reinforced at the bottom and top and at one or more intermediate points by flanged castings 14, the sheathing-plates and cover-plates being of light steel, preferably one-eighth of an inch in thickness. The inside flanges of the Z-bars receive the inside finish of the car, which may be of wood, composite board, or corrugated steel.

Where the cars are to be supplied only with stub-platforms, I construct these stub-platforms so that they will also serve as the car-body end sills, building them up in box-girder form on each side of the end castings 22, which project from the ends of the center sill. At each side of the end castings are horizontal platform-plates 18, said plates being flanged downward at their outer sides and ends and being secured at their ends to the corner-post Z-bars 13. At a short distance below the plates 18 are similar plates 19, the downturned flanges thereof lying flush with the bottom of the car. Said plates 18 and 19 are joined together at their outer sides and curved ends by cover-plates 20, riveted to their flanges, said cover-plates lapping over and being riveted to the vestibule-door-post flanges where they are riveted to the end castings 22. To form the vestibule-doorway, I provide the I-bar door-posts 24, the lower ends of which extend down to the under side of the end castings 22, with their webs riveted in between the upturned flanges 21 on plates 18 and 19 and the sides of the end castings, said end castings being provided with upturned flanges at 23 to register with flanges 21 of the plates 18. The end sheathing-plates 17 are riveted to the webs of the posts 24 by means of angles 25, and the lower ends of said sheathing-plates are riveted to the platform-plates 18 by the transverse angles 27, said angles 27 also serving to stiffen the inward sides of said platform-plates. By this construction it will be seen that the corner-posts of the car are supported from the end castings by box-girder end sills, which also constitute the stub-platforms. Inside of the end sheathing-plates 17 diagonal Z-bars 29 are riveted, said bars extending from the foot of the posts 24 to the top of the corner-post Z-bars 13, thereby bracing the corner-posts at the top against side racking strains. The corner-posts at their lower ends are further braced against longitudinal and transverse strains by the diagonal brace-plates 28, which extend between the center sill and the plates 18, the ends of said diagonal braces being riveted to the under side of the center-sill flanges and to the under side of the plates 18, below the angle-bars 27. For stiffness the brace-plates 28 are provided with downturned flanges along their sides.

The vestibule-diaphragm is secured to the

outer flanges of the posts 24, while to the inner flanges of said posts there are secured the inward portions of the door-casing plates 26. These casing-plates 26 for this type of car are 5 of peculiar form, being pressed from single plates of steel into the shape shown more clearly in Fig. 13, the outer sides of the casings being riveted to the webs of the posts 24 in line with the sheathing-plates 17 by means 10 of angles 25 and the plates being bent around inside the car and pressed inward at 26°, where they are riveted to the inward flanges of the posts. The plates are bent away 15 again from the posts and flanged at 26° to overlap the inside finish. The casing-plates are also provided with rabbets for the door. Threshold-plates 30 pass across between the lower ends of the casings 26, said plates resting at the outside upon the end castings 22 20 and upon the inside upon angles 31, riveted to the inward flanges of posts 24, which angles also support the car-floor. The doorways are completed by pressed-steel lintels 34 passing across between the upper ends of 25 the casings 26 and fastened along their upper edges by angles 35 to the platform-ceiling sheets 33. These ceiling-sheets 33 are of one piece, flanged upwardly along their outer and inner edges, their inner sides extending 30 straight across between the corner-posts and their outer sides being curved so as to pass from the outer flanges of the Z-bars 12 out over the posts 24 in line with the outer flanges of said posts. The ceiling-sheets are also 35 curved upwardly from the sides of the car to the center and are riveted to the upper ends of the posts 24 by means of angles 32, being secured in place at their outer ends by means of the vertical top end plates 36, which are 40 riveted to the outer flanges of the sheets and are bent around the corners of the car in line with the top side plates 38, to which they are united by splice-joints at 39. (See Fig. 2.) The lower edges of these top end plates are 45 reinforced by angles 37. The end sheathing-plates 17 rise to the ceiling-plates 33 and are riveted thereto by means of angles 43.

The sides of the car between the frame-posts are filled in by a lower row of sheathing-plates 16 and an upper row of sheathing- 50 plates 40, said plates being riveted at their ends to the outside cover-plates 9 of the posts, with narrow plates 41 extending between the cover-plates and joining the lower to the upper sheathing-plates. At the ends of the cars diagonal angle-braces 42 are riveted inside of the sheathing-plates 16 and 40 and extend from the bottom of the corner-posts to the top of the first main posts, thereby 55 bracing the end panels of the car against end thrust.

Along the upper sides of the car continuous top side plates 38 extend from end to end, being joined at their ends, as already 60 stated, to the end top plates 36. These top

side plates are of light metal, being preferably one-eighth of an inch thick, and are reinforced at their top and bottom edges by angles 71 and 72, angles 71 extending continuously from one end of the car to the other, 70 and the angles 72 extending between the posts, the sheathing-plates 40 being riveted in with said angles 72 to the plates 38, as shown more clearly in Fig. 4. The outside cover-plates 9 are carried up back of the top 75 side plates and are riveted in between said plates and the posts, as will be seen from an inspection of Fig. 2.

The roof structure consists, primarily, of the continuous angle-bars 45, extending from 80 one end of the car to the other, the ends of said angles being attached to and supported by pairs of triangular bracket-plates 44, riveted to the ceiling-sheets 33, the particular form of these plates being shown more 85 clearly in Figs. 8, 10, 11, and 12. The angles 45 have broad horizontal limbs, slightly curved, and narrower vertical limbs, the dimensions for these angles which I have adopted being six inches by two inches. To the 90 horizontal limbs of these angles the cantilever carline ends of the main posts 8 are riveted, and from their vertical limbs, between each pair of opposite posts, spring the upper-deck carlines 55. The brace-angles 45 95 therefore provide transverse stiffness in the upper car-frame and in connection with the top side plates 38, and the upper-deck side angles 49, all of which are continuous throughout the car-body, act to effectually resist end 100 strains. The upper-deck side angles 49 at the ends are curved downwardly to the top end plates 36 and have their vertical limbs riveted in between the bracket-plates 44.

In the angles between the upper-deck angles 49 and the longitudinal brace-angles 45 at the ends of the car are upper-deck end side plates 46, consisting of single plates of steel pressed into the form shown more fully in Figs. 10 to 12, inclusive. These plates are 110 pressed outwardly along their upper curved edges at 48 and have riveted thereto the upper-deck side angles 49. Along their lower edges the plates are flanged outwardly at 50 to overlap the lower-deck roof, which latter 115 rests upon the longitudinal brace-angles 45. At their inward ends the plates 46 are pressed inwardly at 51 and provided with the vertical flanges 52, to which are secured the ends of the upper-deck sashes 63. The plates 46 120 are supported from the brace-angles 45 by means of plates 47, and by means of this construction the ends of the brace-angles 45 and the upper-deck side angles are securely fastened together and braced one by the other 125 and through the bracket-plates 44 are firmly secured to and braced by the car-end framework.

At the sides of each of the upper-deck carlines side plates 57, corresponding in shape 130

with the end side plates 46 are riveted, their outpressed upper ends 58 receiving and supporting the upper-deck angles 49. These upper-deck side plates are pressed inwardly 5 at each side at 59 and vertically flanged at 60 to receive the upper-deck sashes 63. At their lower edges they are outwardly flanged at 61 to overlap the lower-deck roof and form a water-tight joint therewith. One of these upper-deck side plates is fully illustrated in Fig. 29. Tie-plates 62 unite the upper ends of these side plates to the carlines to further brace the overhang.

At intermediate points between the upper-deck side angles 49 angle-bar braces 53 (four in number in the car herein illustrated) extend from the first upper-deck carlines down to the end top plates 36, said angles being curved to conform with the contour of the upper-deck roof at the car ends. These angles are secured to the ceiling-sheet 33 by means of the flanged gusset-plates 54, and they serve both as roof-supports and as additional braces against end strains. At their inward ends the angles 53 are riveted to the flanges of the upper-deck carlines 55, said upper-deck carlines being of U-shaped cross-section, with their flanged sides placed outward, as described in my said Letters Patent No. 809,920. Between the upper-deck carlines throughout the length of the car horizontal angle-bar braces 56 are riveted in line with the end braces 53, thereby providing continuous lines of horizontal braces from end to end of the car-roof. The upper-deck carlines are pressed into shape from light steel plates, and in order to prevent the side webs of the carlines from being pressed together under end shock I introduce spacers 40 in line with each series of angle-braces between the webs of the carlines, said spacers consisting of pieces of half-inch gas-pipe 64, with bolts or rivets passed through the carlines to hold them in place. (See Fig. 19.)

45 The inside finish or ceiling boards are secured to the upper-deck carlines 55, as shown in Fig. 16, by means of clamping-strips 65, which are attached to the carlines by means of bolts 66, the shanks of said bolts being provided with ears at 67 (see Fig. 18) to engage notched holes 68 (see Fig. 17) provided therefor in the cross-web of the carlines. By these means the bolts are locked against turning in the carlines when the nuts 69 are set up to secure the clamping-plates 65 in place. The nuts 69 used for this purpose are cap-nuts and will be finished on their exposed surfaces and oxidized or otherwise treated in order to provide, together with 55 beaded clamping-strips, an ornamental interior finish. The roof-boards are fastened outside of these upper-deck carlines by means of button-head bolts 70, passing through the carline-flanges, with the nuts set up from the under side of said flanges. The roof-boards

for the lower deck will be fastened to the cross-webs of the carline extensions from the main posts 8 by bolts in a similar manner.

Where the openings are made for the side doors, the side frames must be so strengthened and supported as to avoid weakness in the car-body at these points. To attain the necessary strength and support, I preferably locate these doors so as to come over or at one side of the cross-bearers. In the door construction herein illustrated the door is of such a width as to fill one of the panels between the main-frame posts 8, and I locate the cross-bearers 3 in position to have the posts toward the ends of the car resting directly thereon. I also provide an additional cross-bearer at the center of the car to support the car-body between door-openings. To strengthen the side sills at the door-openings, I provide a box-girder construction between the door-posts, the details of which are more fully illustrated in Figs. 23 to 26, inclusive. This consists of a sill-plate 73, riveted to the side sill and bent inward at the top to form a threshold, the inner edge at 74 overlapping 90 the car-floor. Inside of the sill-plate is a supporting-plate 76, flanged along its lower edge and secured to the side sill 6 by means of the cover-plate 78. This plate 76 is pressed inward between the posts 8 and flanged at 95 79 to form a rest for the threshold portion of the sill-plate 73, there being riveted in between said flange and the sill-plate a floor-supporting plate 80 of Z-shaped cross-section. The ends of the plate 76 extend out 100 vertically at 81 to overlap the posts 8, being riveted thereto and to the inside cover-plates 10. By this construction it will be seen that I have provided a strong box-girder support 105 extending between the door-posts at the base of the doorway. At the top of the doorway the posts are joined together by a channel lintel-plate 90, having its outside flange riveted to the lower edge of the top side plate 38, and at the inside the door-frame is further 110 strengthened by the Z-bar 91, which extends across between posts above the lintel and serves as a track for the door-hangers. (See Fig. 4.) It will also be understood that the longitudinal brace-angles 45, together with 115 the top side plates 38, act in conjunction with the cantaliver-carline ends of the main posts to supply the necessary strength to the car-frame over the door-openings.

The side door-casings for the doorways 120 consist of pressed plates 82, the outward sides of which act as cover-plates for the posts 8 and have riveted thereto the sheathing-plates 16 and 40. These side casing-plates are curved inwardly and flanged at 125 their inward sides at 83 to overlap the inside finish of the car, the inside cover-plates 10 being provided with flanges at 84, to which these casing-plates are riveted. Heavier protecting-plates 85 rise from the sill-plate 130

73 part way up the casing-plates 82, these protecting-plates being pressed outward at their lower ends at 86 to overlap upturned flanges 75 on the sill-plate 73, thereby forming water-tight joints at these points and further binding the sill-plate to the frame-posts. The door-casings are further strengthened by reinforcing-castings 87, (see Fig. 27,) riveted in between the casing-plates 82 and the side webs of the posts 8, these reinforcing-castings being located where the handhold-rods, &c., are attached and at intervals apart sufficient to add the necessary strength and support to the casing-plates. (See Figs. 4 and 27.)

Should the doorways be narrower than the panels between the main frame-posts, I may utilize one of the posts for a door-post and construct the other door-post in the manner illustrated in Fig. 28, wherein a vertical flanged plate 88 takes the place of the post 8, the casing-plate 82 being riveted to the outer and inner flanges of said post and being further secured thereto by means of reinforcing-castings 89. This construction may be utilized in the narrow doorways for postal cars and the like, and if the doorway must be so located that the main frame-posts 8 can be utilized for neither of the door-posts then both posts will be formed as illustrated in Fig. 28, the box-girder-sill construction remaining the same. Where narrow doorways are provided, as in postal cars, hinged doors may be used instead of the sliding doors here shown, in which case the casing-plates 82 will have rabbets pressed therein, as shown in the end door-casings.

Where this car is used in connection with four-wheel trucks and said trucks are so located that the side bearings will be positioned between the main frame-posts, I reinforce the car sides by means of pressed-steel side bearing-braces 93 of U-shaped cross-section, riveted at 94 to the projecting ribs 95, formed on side bearing-castings 92, which latter are riveted to the under-side of the side sills 6. (See Figs. 2, 3, 4, 30, and 31.) The cross-webs of these side bearing-braces 93 are riveted to the sheathing-plates 16, while the inner flanges receive the interior finish of the car. The portion 94 of the brace is pressed inward, so as to clear the side sills 6, as will be seen from an inspection of Fig. 4. At the upper end the side webs and flanges 55 of the brace are pressed outward into line with the cross-web at 96, and this portion is riveted in between the belt-strip 41 and a reinforcing T-bar 97, riveted in between posts to further stiffen the side panels at these points. These reinforcing T-bars 97 are further used to stiffen the panels where the window-openings occur, and in the baggage-car these window-openings will be framed in by one-piece casing-plates 98 and 99, said casing-plates being pressed to Z-shaped cross-section,

the outside flanges of the plate 99 overlapping and being riveted to the sheathing-plates 40 and the inside flanges of the plates 98 overlapping the inside finish. The abutting flanges of these plates are provided with 70 registering bolt-holes through which pass the bolts by which the window-sash are permanently secured in place in the window-frame. The frame-plates 98 may also be provided with grating-rods to protect the window-glass 75 from the inside.

The flooring for this type of car consists of corrugated plates 100, laid transversely across the car upon longitudinal joist-plates 101 and 102, rivet to the center sill and to 80 the main frame-posts. The joists 101 are formed from Z-bars and the joists 102 from channel-bars. Above the floor-plates 100 there is a plastic filling 103, over which are laid floor-boards 104. Below the floor-plates are subfloor-boards 105, arranged in two rows on each side of the car, said boards resting with their inner ends upon the cover-plate of the center sill and being held thereon by means of lips 106, pressed out from the 90 webs of the joists 101. (See Fig. 4.) The outer ends of the boards rest upon the lower flanges of the joists 102 and are secured in place by similar lips 106, pressed out from the webs of said joists. The intermediate ends 95 of the subfloor-boards have attached to them angles 108 by bolts or rivets, and said angles are bolted to the lower ends of longitudinal angle-plates 107, riveted to the floor-plates 100. The spaces between the floor-plates 100 and the subfloor may be air-space or may be filled with mineral wool or other material, as desired, and the subfloor-boards may be readily removed or replaced for repairs or other purposes by simply unbolting the angles 105 108 from the hanger-plates 107 and dropping the subfloor-boards out of engagement with the joists 101 and 102.

While I have described my improved framework in connection with a baggage-car, 110 it will be understood that the principal features thereof, especially the skeleton framework, may be applied to all cars for passenger service, passenger, postal, and express cars, as well as the baggage-car taken for 115 illustration. In fact I have already shown the framework as applied to passenger-cars in my copending applications, Serial Nos. 303,405 and 304,534, filed February 28 and March 6, 1906, respectively. The car sides 120 between the main frame-posts will be modified to receive the different window or side door frames as called for in the different types of car, and the side bearings will be modified to meet the requirements where four-wheel 125 or six-wheel trucks are used.

What I claim, therefore, as my invention without confining myself to any particular type of car, and desire to secure by Letters Patent, is—

1. In a car-frame constructed without body-bolsters, the combination, with a center sill and side sills supported thereby upon cross-bearers projecting from the sides of the center sill at points intermediate the ends, of a series of posts rising from the side sills, cross-braces extending from the center sill to the side sills in line with each pair of opposite posts, carlines connecting opposite posts, top side plates riveted to the posts at their upper ends, and longitudinal brace members extending between the carlines throughout the length of the car.
2. In a car-frame constructed without body-bolsters, the combination, with a center sill and side sills supported thereby upon cross-bearers projecting from the sides of the center sill at points intermediate the ends, of a series of posts rising from the side sills, lower-deck carlines formed by inturned extensions from said posts, continuous longitudinal brace members riveted to the ends of said carline extensions, upper-deck carlines riveted to said longitudinal braces in line with opposite posts, cross-braces extending from the center sill to the side sills in line with each pair of opposite posts, top side plates riveted to the posts at their upper ends where the lower-deck carlines spring therefrom, and intermediate longitudinal brace members extending between the upper-deck carlines throughout the length of the car.
3. In a car-frame, the combination, with the side sills, of posts rising therefrom and having lower-deck carlines formed by in-turned extensions from the upper ends thereof, longitudinal angles having broad horizontal limbs riveted to the inward ends of said carlines on each side of the car, and upper-deck carlines passing across between opposite posts and riveted to the vertical limbs of said angles.
4. In a car-frame, the combination, with the upper and lower deck carlines, of longitudinal brace-angles to which said carlines are attached at their points of juncture, said brace-angles having broad horizontal limbs to provide transverse stiffness and being supported and braced at the ends from the car end frames.
5. In a car-frame, the combination, with the frame-posts having lower-deck carlines formed by inturned extensions from the upper ends thereof, of longitudinal brace-angles riveted to the ends of said carline extensions at each side of the car, upper-deck carlines riveted to said brace-angles between opposite lower-deck carlines, upper-deck side angles attached to the upper-deck carlines, and top side plates riveted to the posts below the spring of the lower-deck carlines, said brace-angles, side angles and side plates extending continuously from end to end of the car and being joined together and braced at their ends by the car end frames.
6. In a car-frame, the combination, with the end frames having platform ceiling-sheets, of bracket-plates rising therefrom in line with the points of juncture between the upper and lower deck carlines, continuous brace-angles having their ends supported by said brackets, and the upper and lower deck carlines joined to said brace-angles at their points of juncture.
7. In a car-frame, the combination, with the end frames having platform ceiling-sheets, of pairs of bracket-plates rising therefrom in line with the points of juncture between the upper and lower deck carlines, longitudinal brace-angles having their ends supported by said bracket-plates, and upper-deck side angles having their ends curved down to the ceiling-sheets and secured between the bracket-plates.
8. In a car-frame, the combination, with the end frames, of longitudinal brace-angles supported thereby in line with the points of juncture between the upper and lower deck carlines, upper-deck side angles positioned above said brace-angles, and deck-end side plates riveted in between said brace-angles and side angles at the ends of the car.
9. In a car-frame, the combination, with the end frames having platform ceiling-sheets 33, of the bracket pairs 44 rising therefrom, longitudinal brace-angles 45 having their ends riveted to said bracket pairs, upper-deck side angles 49 having their ends curved down to the ceiling-sheet and riveted in between the bracket pairs, and the deck-end side plates 46 riveted in between the brace-angles and side angles at the ends of the car, all substantially as herein shown and described.
10. The deck-end side plates of pressed steel, triangular in form, curved along their upper edges, pressed outwardly and flanged along said edges to receive the upper-deck side angles, outwardly flanged along their bottom edges to overlap the lower-deck roof, and pressed inwardly and flanged along their vertical edges to receive the upper-deck sashes.
11. In a car-frame comprising posts having lower-deck carlines projecting from the upper ends thereof and upper-deck carlines passing across between opposite lower-deck carlines, the combination therewith of continuous longitudinal brace-angles riveted to said carlines at their points of juncture, upper-deck side plates riveted to the upper-deck carlines, upper-deck side angles riveted to the upper ends of said plates and extending continuously from end to end of the car, deck-end side plates joining the side angles to the brace-angles at the ends of the car, and supporting-brackets whereby the side and brace angles are united to the car end frames.
12. The upper-deck side plates comprising vertical plates pressed outwardly and flanged

at their upper ends to receive the upper-deck side angles, outwardly flanged at the bottom to overlap the lower-deck roof, and pressed inwardly and flanged along their vertical sides to receive the upper-deck sashes.

13. The combination, with the upper-deck carlines of U-shaped cross-section, of longitudinal brace members extending between carlines and riveted to the flanges thereof, and spacers positioned between the vertical webs of the carlines in line with said brace members.

14. In a car-frame, the combination with the posts and upper and lower deck carlines, of longitudinal brace-angles riveted to the carlines at their points of juncture, platform ceiling-sheets passing across between the corner-posts at each end of the car, to which the ends of said brace-angles are secured, top side plates riveted to the posts, top end plates passing around the ceiling-sheets and joined to the top side plates, and longitudinal brace members joining the upper-deck carlines, said brace members at the ends of the car being bent down and riveted to the ceiling-sheets.

15. In a car-frame, the combination, with a center sill and angle-bar side sills, of frame-posts having a U-shaped cross-section placed with their flanged sides inward and having their cross-webs at the base riveted inside the vertical limbs of the side sills, cross-braces extending out from the center sill and riveted at their outer ends to the under side of the horizontal limbs of the side sills beneath the posts, outside cover plates riveted to the cross-webs of the posts and extending down and riveted in with the posts outside the side sills, and inside cover-plates riveted to the post-flanges and having their lower ends flanged and riveted to the cross-braces.

16. In a car-frame, the corner-posts comprising pairs of Z-bars placed with their webs at right angles and their outside flanges turned toward one another, curved cover-plates riveted to said outside flanges, and spaced reinforcing-castings riveted in between the webs and cover-plate.

17. In a car side frame, the combination, with a side sill and posts rising therefrom, of outside cover-plates riveted to the posts, a top side plate riveted to the posts at their upper ends outside the cover-plates, upper and lower sheathing-plates overlapping the side sill at the bottom and overlapped by the cover-plates and top side plate at the ends and top, longitudinal splice-plates uniting the upper and lower sheathing-plates between cover-plates, and reinforcing T-bars placed inside said splice-joints where the upper sheathing-plates are cut for window-openings.

18. In a car side frame, the combination, with a side sill and posts rising therefrom, of a light continuous top side plate riveted to

the posts at their upper ends, lower-deck carlines formed by inturned extensions from the upper ends of the posts, and a longitudinal brace-angle having a broad horizontal limb riveted to the inward ends of said carlines and extending continuously from end to end of the car.

19. In a car side frame, the combination, with a side sill and posts rising therefrom, of a light top side plate riveted to the posts at their upper ends and reinforced along its top and bottom edges, lower-deck carlines projecting inward from the upper ends of the posts, and a longitudinal brace-angle having a broad horizontal limb riveted to the inward ends of said carlines, said side plate and brace-angle extending continuously from end to end of the car and being united to the car end frames at each end thereof.

20. In a car side frame, the combination, with a side sill and an outside sheathing-plate rising therefrom, of a side bearing-casting riveted to the under side of the side sill and projecting inwardly therefrom, and a vertical brace member riveted inside the sheathing-plate and having its lower end bent around the side sill and riveted to said casting.

21. A car side frame comprising a side sill, posts rising therefrom, sheathing-plates between posts riveted to the side sill, side bearings attached to the under side of the side sill over the wheel-trucks between posts, and vertical braces extending from said bearings upward inside the sheathing-plates and riveted thereto.

22. The side bearing-casting having the brace-webs substantially as herein shown and described.

23. The side bearing-brace of U-shaped cross-section, pressed into the form substantially as herein shown and described.

24. In a car-frame of the type described, the combination, with the cross-bearers, of jacking-castings riveted in therewith where the cross-bearers receive the side sills.

25. In a car-frame of the type described, the combination, with the cross-bearers comprising pairs of cantaliver-plates projecting from a center sill, of jacking-castings riveted in between the outer ends of said cantaliver-plates, and side sills passing across and riveted to the upper sides thereof.

26. The jacking-castings in combination with the cross-bearers substantially as herein shown and described.

27. In a car-frame, an upper-deck roof comprising carlines of U-shaped cross-section having their side webs flanged and placed with said flanges facing outward, and the roof-sheathing secured thereto by bolts passing through the flanges and set up from the inside.

28. In a car-frame having upper-deck carlines of U-shaped cross-section, the combina-

tion therewith of ceiling-clamping strips secured to the carlines by bolts passing through the cross-webs thereof.

29. The combination with a carline having an inside cross-web, of a series of bolts projecting through said web and secured against turning therein, a ceiling-clamping strip through which said bolts pass, and cap-nuts on the bolts to hold said strip in place.

30. In a car side frame, the combination, with a sheathing-plate having a window-opening therein, of an outside metal frame of Z-shaped cross-section having its outer flanges overlapping and riveted to the sheathing-plate, and a corresponding inside frame of Z-shaped cross-section having its inner flanges overlapping the inside car finish, the abutting flanges of the two frames being provided with registering holes to receive bolts whereby the sash is secured in place.

31. A car-frame comprising side sills supported from a center sill by cross-bearers, and having side doorways positioned over or directly adjacent the cross-bearers, substantially as herein shown and described.

32. A car-frame comprising side sills supported from a center sill by cross-bearers, and having side doorways positioned over or directly adjacent the cross-bearers, the side sills being strengthened between the door-posts by box-girder door-sills built up from the side sills.

33. In a car-frame, the combination, with a side sill, of a side-door frame comprising posts rising from the side sill, a door-sill plate rising from the side sill between posts and bent inward at the top to form a threshold, and a plate passing across between posts at the inside, said plate being attached to the side sill at the bottom and to the threshold portion of the door-sill plate at the top.

34. In a car-frame, the combination, with an angle-bar side sill having its vertical limb placed outward, of a side-door frame comprising posts rising from the side sill back of its vertical limb, a door-sill plate riveted to the outside of the side sill between posts and bent inward at the top to form a threshold, a plate riveted to and passing across between posts at the inside, said plate being pressed outward between posts, flanged along its upper edge and riveted to the threshold portion of the sill-plate, and a cover-plate riveted to the horizontal limb of the side sill and to a flange at the lower edge of said inside plate.

35. In a side-door frame for railway-cars, the combination, with the side sill and the posts rising therefrom, of a door-sill comprising the sill-plate 73 riveted outside the side sill, the inside plate 76 passing across between posts and pressed to the form substantially as herein shown and described, the floor-supporting plate 80, and the bottom cover-plate 78.

36. In a side-door frame for railway-cars, the combination, with a side sill and posts rising therefrom, of a sill-plate riveted to the side sill between posts and bent inward to form a threshold, said threshold portion being flanged upwardly at each end, and side casing-plates attached to the posts and pressed outward where they meet the threshold to overlap said flanges.

37. In a side-door frame for railway-cars, the combination, with a side sill and posts rising therefrom, of a door-sill plate riveted to the side sill between posts, and side casing-plates comprising outside cover-plates for the posts adapted to receive the outside sheathing-plates, said casing-plates being cut at the bottom to fit the sill-plate and being bent inward above the sill-plate and flanged along their inward edges to overlap the inside finish.

38. In a side-door frame for railway-cars, the combination, with pressed-steel door-posts having inside cover-plates riveted thereto, of side casing-plates comprising outside cover-plates riveted to the posts and bent inward to meet the inside cover-plates, the inside cover-plates being flanged along their edges to receive the casing-plates, and said casing-plates being flanged along their inward edges to overlap the inside finish.

39. In a side-door frame for railway-cars, the combination, with the posts and a sill-plate having a threshold portion provided with upturned flanges at each end, of casing-plates bent around and riveted to the posts, and protective plates rising part way up the casing-plates from the sill-plate, said protective plates being pressed outward at the bottom to overlap the threshold-flanges.

40. In a side-door frame for railway-cars, the combination, with the posts and a sill-plate, of side casing-plates comprising outside cover-plates riveted to the posts and bent inward above the sill-plate, a top side plate passing across the upper ends of the posts outside the upper ends of the casing-plates, and a channel lintel-plate fitted between the casing-plates and riveted to the lower edge of the top side plate.

41. In a car having a continuous center sill, an end frame comprising an end casting projecting from the end of the center sill, end door-posts rising from the sides of said end casting, horizontal end-sill plates projecting laterally from the end casting, corner-posts rising from the outer ends of the sill-plates, and a ceiling-sheet passing across between corner-posts and having the door-posts riveted thereto.

42. In a car having a continuous center sill, an end frame comprising an end casting projecting from the end of the center sill, I-bar door-posts fitted to the sides of the end casting and having their webs riveted there-

to, horizontal end-sill plates riveted in with said webs to the sides of the end casting, corner-posts rising from the outer ends of the sill-plates, a ceiling-sheet passing across between the corner-posts and having the door-posts riveted thereto, and end sheathing-plates extending from the door-post webs to the corner-posts and from the end-sill plates to the ceiling-sheet.

43. In a car having a continuous center sill and end castings projecting therefrom, the end-sill construction comprising upper and lower horizontal sill-plates projecting laterally from the sides of the end castings, to which they are riveted, and outside cover-plates riveted to the flanged edges of said plates and to the end castings.

44. In a car having a continuous center sill and end castings projecting therefrom, the end sills comprising horizontal plates projecting laterally from the sides of the end castings, and diagonal brace-plates extending from the center sill to the outer ends of said plates.

45. In a car having a continuous center sill and end castings projecting therefrom, the end frames comprising door-posts having web portions riveted to the sides of the end castings, horizontal plates projecting laterally from the end castings and riveted in with the door-posts, corner-posts rising from the outer ends of said plates, end sheathing-plates riveted between the door-post webs and the corner-posts adjacent the inside edges of said horizontal plates, whereby the projecting portions of said plates will serve as stub-platforms, and ceiling-sheets passing across between the corner-posts and projecting out over the door-posts, the upper ends of which are riveted thereto.

46. In a car having a continuous center sill and end castings projecting therefrom, the end frames comprising door-posts having web portions riveted to the sides of the end castings, horizontal platform-plates projecting laterally from the end castings and riveted in with the door-posts, corner-posts rising from the outer ends of said plates, and diagonal braces extending from the door-posts

at their lower ends to the corner-posts at 50 their upper ends.

47. The end castings having lateral wings adapted at their extremities to have door-posts attached thereto substantially as herein shown and described. 55

48. The combination, with the webbed door-posts, of the casing-plates 26 having their outside portions riveted to the post-webs and their inside portions riveted to the post-flanges. 60

49. The casing-plates 26 having the inside and outside portions connected by a curved and rabbeted cross-web, the inside portion being outwardly channeled at 26^a for the purpose set forth. 65

50. The combination, with a car-frame comprising a center sill, depressed side sills and posts for the sides rising from the side sills, of floor-plates resting on longitudinal joists comprising Z-bars riveted to the top of the center sill at each side and channels riveted to the posts, longitudinal hangers depending from the floor-plates between the center sill and side sills, angle-bars secured to the lower edges thereof, and subfloors resting upon said angles, upon the center sill and upon the bottom flanges of the side channels, the webs of the Z-bars and channels having tongues pressed out therefrom and bent down to engage the upper sides of the floors. 75 80

51. The combination, in a car-frame, of transverse floor members resting upon longitudinal frame members, longitudinal hangers depending from said transverse members between the longitudinal members, longitudinal subfloor-supports in line with the longitudinal frame members provided with sockets to receive the ends of subfloor members, and the subfloor members adapted to have one end thereof inserted in said sockets and the other end removably attached to the longitudinal hangers. 85 90

In testimony whereof I have affixed my signature in presence of two witnesses.
